UNITED STATES PATENT OFFICE.

HARRY J. ANDERSON, OF CHICAGO, ILLINOIS, ASSIGNOR TO NEWMAN BROS. CO., OF CHICAGO, ILLINOIS.

MECHANICAL MUSICAL INSTRUMENT.

1,171,827.

Specification of Letters Patent. Patented Feb. 15, 1916.

Application filed May 13, 1911. Serial No. 626,986.

To all whom it may concern:

Be it known that I, HARRY J. ANDERSON, a citizen of the United States, residing at Chicago, in the county of Cook and State of Illinois, have invented a certain new and useful Improvement in Mechanical Musical Instruments, of which the following is a full, clear, concise, and exact description, reference being had to the accompanying drawings, forming a part of this specification.

My invention relates to the mechanism of an automatic musical instrument, and has as one of its objects the provision of a device in which all the major elements of such a mechanism may be mounted upon a single support so that the whole may be installed or removed from the instrument in the easiest manner possible, and also to permit the inspection of the interior without disconnecting such parts from the instrument.

A further object is to arrange the parts in a symmetrical manner so that passages between the bellows and the operating mechanisms shall be of equal length, while providing an efficient and practical arrangement for varying the tone or the time of the music.

Further objects will appear in the particular arrangement of parts hereinafter described.

Figure 1 is a front elevation partly in section of my improved arrangement taken on line 1—1 of Fig. 2; Fig. 2 is a cross section on line 2—2 of Fig. 1, showing the device as it would appear when mounted in a piano or other instrument; Fig. 3 is a detail view of the central chest shown in section in Figs. 1 and 2, and showing the arrangement of ports; Fig. 4 is a detail of the longitudinal passages appearing in Fig. 1.

Throughout the drawings similar reference characters denote the same part.

Referring more particularly to the drawings, 1 and 1^a are base members which are hinged to the toe rail 2, of the piano as shown at 3. The members 1 and 1^a carry the whole mechanism with which this invention has to deal. Upon the back of the members 1 and 1^a are mounted bellows 4, connected by means of ports 5 with the interior of longitudinal passages 6 and 7, and with the atmosphere by ports 11. The passages 6 and 7 are formed by strips 8^a fastened upon the face of a board or plate

50 carried by the members 1 and 1^a and extending across their entire width. Parallel with passages 6 and 7 is a passage 8 formed in a similar manner, but divided into four sections by three blocks such as 9, whereas 60 passages 6 and 7 are uninterrupted throughout their entire length. A board or plate 37 covers the passages 6, 7 and 8.

At the outer ends of members 1 and 1^a are the usual reservoir pneumatics 10—10, 65 covering the ends of the passages 6, 7 and 8 and connecting directly thereto. At the two outer blocks 9 are governor pneumatics 12—12 for regulating the air to the motor and key striking pneumatics respectively. 70 Ports 13—13 connect pneumatics 12 with the passage 8 at each side of the blocks 9. The central block 9, however, is shown in section in Fig. 1 and has no passage leading around it. At the upper edge of the members 1 and 1^a, covering the passages 7 and 8 at the center, is a chest 14 provided with three chambers 15, 16 and 17, and having an offset portion serving as a valve box provided with coöperating chambers 18, 19 and 20, lying below the floor 38 of the chambers 15, 16 and 17, as shown in the broken away portion of Fig. 1. Chamber 15 connects with passageway 8 by the port 21 and with chamber 18 by the port 22. Chamber 16 connects with passage 7 by the port 23 and with chamber 19 by the port 24, while chamber 17 connects with passage 8 by the port 25, and with chamber 20 by the port 26. A passage 27 leads from chamber 18 to the key striking mechanism, and passage 28 leads from chamber 20 to the motor pneumatics. Suitable valves are provided in chambers 18 and 19 for controlling the passages shown which connect chambers 18, 19 and 20 and passage 90 27. Valve 29 controls the port 27 and valve 30 controls the port 31, while valve 32 controls the port 33. The ports 21, 22, 23, 24, 25 and 26 are formed in a board or plate 38, while a board or plate covers the chest 14, forming one side of the chambers 15, 16 and 17. The valve 32 is controlled by a lever 36^a and a rod 55 connected therewith. The valve 29 is actuated by a rod 53 and the valve 51 by a rod 54.

It will be seen that chamber 16 is subject to the direct action of the bellows, while the tension in chambers 15 and 17 is regulated by governor pneumatics 12. Therefore when valve 29 is open and valve 30 is 110

closed, the key striking mechanism will be operated by either regulated tension from the chamber 15 or by direct tension from the chamber 16, according to whether the 5 expression valve 32 is open or closed.

It will be understood that valve 30 is always closed when 29 is open, and vice versa. When it is desired to rewind the music roll 10 valve 29 is closed and 30 open, giving direct tension upon the motor pneumatics for quick rewinding. Any suitable mechanism 15 may be supplied for operating the valves 29, 30 and 32. Valve 32 is shown as governed by a lever 35 which is attached to a rod 36 which may be controlled by any means desired. The ordinary tempo valve 51 is placed to govern the port 26.

Particular attention is called to the fact 20 that whenever it is desired to inspect the apparatus of my device, member 1 and all the mechanism carried thereby may be swung forward without disturbing any of the parts, and this irrespective of whether the treadles 34 are folded or not.

25 Having thus described my invention what I claim as new and desire to secure by Letters Patent is:

1. In an automatic piano player in combination, pumping bellows, storage bellows, 30 a wind way rigidly attached to said pumping bellows to which said storage bellows are connected, a valve box or chest, connections leading from said box for note sounding and motor mechanism, said box being 35 provided with a direct connection with said wind way, a second wind way provided with a governing pneumatic connecting one of said storage bellows with said box, a third wind way also provided with a governing 40 pneumatic connecting another of said storage bellows with said box and valve means mounted in said box for connecting said first mentioned wind way with either the note striking or motor connection at the will of 45 the operator.

2. In an automatic piano player in combination, a pumping bellows, a pair of storage bellows, a wind way connecting said pumping bellows with both of said storage 50 bellows, a second wind way leading from one of said storage bellows and provided with a governing pneumatic, a third wind way leading from the other of said storage bellows also provided with a governing pneumatic, said second and third wind ways being in alinement, and a valve box to which 55 said second and third wind ways are connected provided with means for controlling the air in said wind ways.

60 3. In a pneumatic piano player in combination, a feeder bellows, a pair of storage bellows, a wind way connecting said feeder bellows with both of said storage bellows, a valve box mounted intermediate of said 65 storage bellows, a wind way provided with

a governing pneumatic leading from each of said storage bellows to said valve box, and means carried by said box for controlling the air in said last mentioned wind ways.

4. The combination of a pair of reservoir 70 pneumatics, a built-up structure extending from one of said pneumatics to the other, said structure containing one or more unobstructed windways connecting said pneumatics and containing also two windways of 75 equal length separated from each other, but arranged in alinement, and connected one to each of said pneumatics, and governing or regulating pneumatics being connected to control said two last mentioned windways, 80 said governing pneumatics being carried on the outer surface of said structure.

5. In an automatic piano player in combination, a pair of pumping bellows, a plurality of wind ways connecting said bellows 85 and extending beyond said bellows, a pair of storage bellows connected to the ends of said wind ways, a pneumatically governed wind way leading from one of said storage bellows and a second pneumatically governed 90 wind way leading from the other of said storage bellows, and pneumatic governors for the two last mentioned windways.

6. In a device of the class described in combination, a base member, bellows carried 95 on one side of said base member, means providing a plurality of channels on the other side of said base member, ports connecting said bellows with two of said channels, reservoir pneumatics carried at the ends of said 100 base member connecting with said channels, a chest carried over said channels provided with three chambers and with a port connecting one of said chambers with one of the channels which connects in turn with the 105 bellows, and also with ports connecting the other two chambers with a third channel.

7. An automatic musical instrument comprising in combination, a plurality of reservoir pneumatics, a wind way connecting 110 said pneumatics, a wind way provided with governing means leading from one of said reservoirs, and another wind way also provided with governing means leading from another of said reservoirs.

8. In an automatic musical instrument in combination, note striking mechanism, a pneumatic motor, tension producing means, a plurality of pneumatic governors, a valve box having a central compartment and a 120 compartment on each side of the central one, said central compartment being connected directly to said tension producing means, and said side compartments being connected each to one of said pneumatic 125 governors.

9. In an automatic musical instrument in combination, a source of unregulated wind, a plurality of pneumatic governors, a valve box having a central compartment and a 130

compartment on each side of the central one, said central compartment being connected to said source of unregulated wind, said side compartments being connected each to a separate one of said pneumatic governors, and valve connections between the central and the two side compartments.

10. In a device of the class described in combination, an auxiliary chest comprising a board or plate forming a floor, partitions forming chambers within said chest, a valve box carried below said floor, partitions in

said valve box forming chambers equal in number to said first mentioned chambers, said floor having ports therein for connection to tension producing means and also ports leading to the chambers in said valve box.

In witness whereof, I hereunto subscribe my name this 28th day of April A. D., 1911. 15

HARRY J. ANDERSON.
